CLAIM

We claim the ornamental design for an automatic cleaner for modular air conditioner, as shown and described.

DESCRIPTION

FIG. 1 is a front perspective view of an automatic cleaner for modular air conditioner showing a new design;

FIG. 2 is a rear perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view showing a state of use thereof.

The broken lines shown in the figures are for the purpose of illustrating portions of the automatic cleaner for modular air conditioner and form no part of the claimed design. The broken lines shown in FIG. 9 are for the purpose of illustrating environmental structure and form no part of the claimed design.
